COOLING BED

Gustaf L. Fisk, New Fairfield, Conn., and Edward T. Peterson, Reading, Pa.; said Fisk assignor to Mesta Machine Company, West Homestead, Pa., a corporation of Pennsylvania, and said Peterson assignor to Birdsboro Steel Foundry & Machine Company, Birdsboro, Pa., a corporation of Pennsylvania

Application April 6, 1942, Serial No. 437,794

8 Claims. (Cl. 80—42)

This invention relates to cooling beds for a variety of products and, in particular, to cooling beds having provisions for the annealing of flat bars in a continuous pack.

Cooling beds having provisions for pack-annealing have been used for many years. Certain forms of such beds are shown in Fisk Patent No. 1,761,470, Fisk and Peterson Patent No. 1,954,123 and Peterson Patent No. 1,834,728. The known cooling beds, however, have been capable of annealing rolled bars of relatively narrow widths only, say up to 4". More recently, it has appeared desirable to subject much wider bars, e. g., up to 8" wide, to pack-annealing, but this cannot be accomplished successfully by the structures and mechanisms known previously. Furthermore, it has been the practice to deliver bars on edge into a pack for annealing, placing them on the bed in an inclined position against lateral support. With this method the stability of the pack is often precarious in its early stages of formation. In case of the first bar thus delivered for annealing, for instance, the friction between the lower edge of the bar and the bed surface, and the friction caused by the reaction from the lateral support due to the weight of the bar in its inclined position, are the only forces which maintain the bar in equilibrium. In addition, when pack-annealing bars on beds of known types, it is found that the bars do not readily separate from each other at the discharge side of the pack. Instead, the bars have a tendency to "shingle" so that considerable time and labor are required to separate them preparatory to subsequent handling.

We have invented a novel cooling bed which fully overcomes the aforementioned objections to such beds as previously known. In a preferred embodiment, we provide latch members and retreating abutments adapted to support a pack on the entry side and discharge side respectively, with the flat bars of the pack standing on edge during the cooling process as they progressively move across the pack-annealing section of a cooling bed. The latch members and the retreating abutments depend from supports above the pack-annealing section of the cooling bed, which supports are mounted for vertical movement to adjust the elevation of the latch members and the retreating abutments to suit bars of different widths. The latch members, pivoted on the supports, are displaced each time a bar is added to the pack and then restored by gravity to holding position, while the retreating abutments, guided by the supports, retreat to make room for each

bar added to the pack until the pack has grown to predetermined size. After the pack has grown to reach the discharge side of the pack-annealing bed section, means are provided for then separating the leading bar from the remaining bars constituting the pack, as the packing process is continued, in such manner as to avoid any "shingling" and to insure a prompt and positive separation.

10 For a complete understanding of the invention, reference is made to the accompanying drawings, which will be described and explained in detail hereinafter. In the drawings:

Figure 1 is a typical transverse section through a cooling bed with parts in elevation, showing latch member, retreating abutment, their support and operating rig, in accordance with the present invention, the parts being in position for packing relatively wide flat bars;

15 Figure 2 is a partial side elevational view of the apparatus of Figure 1, showing the operating rig for the arms supporting the latch members and the retreating abutments;

20 Figure 3 is a transverse section of the same cooling bed with the packing mechanism and its operating rig in position for packing of relatively narrow flat bars;

25 Figure 4 is a top plan view of one of the arms with latch member and retreating abutment;

30 Figure 5 is a transverse section of the same cooling bed with the pack-supporting mechanism and its operating rig in position to clear the bed or to restore the retreating abutments to starting position;

35 Figure 6 is a partial side elevational view of the apparatus of Figure 5 showing the operating rig for the pack-supporting mechanism in corresponding position;

40 Figure 7 is a cross sectional view, on line VII—VII of Figure 5, through the retreating abutment and the arm supporting it;

45 Figure 8 is a typical transverse section through a cooling bed showing a modified form of the invention, with parts in position for packing of relatively wide flat bars; and

Figure 9 is a transverse section through the same cooling bed shown in Figure 8, but with parts in position for packing of relatively narrow flat bars.

50 Referring now in detail to the drawings and, for the present, to Figure 1, hot bars 1 emerging from a rolling mill, are delivered along one side of a cooling bed on a run-in conveyor comprising a plurality of motor-driven rollers 2. Aprons 3, when elevated by suitable mechanism, lift the

hot bars 1 off the rollers 2, to arrest their motion and elevate them sufficiently to clear the upper edge of aprons 4. The aprons 3 are carried on a beam 3a. Bell cranks 3b pivoted in the main frame castings of the bed each have an arm supporting the beam and are actuated by a thrust rod 3c pivoted to the other arm of each crank. Side guards 5, movable longitudinally of the rollers 2, then serve as a "kick-off," by displacing the bars 1 laterally from the rollers 2. The side guards 5 are simply cast flanged plates of relatively short length disposed longitudinally of the conveyor for angular sliding on aprons 3, each plate being pivoted adjacent one end of a vertical pin 5a. Links 5b are pivoted to each plate adjacent the other end and to one of a plurality of cranks spaced along a longitudinal shaft 5c. Thus by rocking the shaft, one end of each plate 5 swings about the pivot pin 5a at its other end.

The cooling bed comprises, in addition to the sloping skid section formed by the aprons 4, an arcuate skid section 6, a packing section 7, a sloping discharge section 8 and a final cooling section 9. The various sections of the bed are composed of skids formed from suitable metal bars or aprons supported in any convenient manner, for example as disclosed in the prior patents above mentioned. The final cooling section 9 may conveniently take the form illustrated at 19 in Patent No. 1,954,123. The bars forming the arcuate section 6, packing section 7 and discharge section 8 are pivoted on a longitudinal shaft 10, whereby they may be tilted to discharge bars delivered thereto immediately, in case pack annealing is not desired. To this end, the bars forming sections 6, 7 and 8, are secured to a beam 6a. A shaft 1a has eccentrics spaced therealong provided with links 8a pivoted to the beam.

The shaft 10 is also provided with packing arms 11 disposed between adjacent bars or aprons of the sloping skid section 4 and the arcuate skid section 6. These arms serve, on rotation of shaft 10, to move a bar from a position at the foot of the sloping skid section 4 upwardly over the arcuate skid section 6 to the entering side of a pack of bars disposed on edge, indicated generally at A. The bars are delivered to the sloping skid section 4, as previously indicated, by the laterally movable side guards 5, which act as a "kick-off."

The novel pack-supporting means which we have invented particularly for the purpose of maintaining a pack of extra wide bars as well as packs of bars of ordinary widths will now be described. It comprises a plurality of arms 12 spaced along the length of the cooling bed. Each arm 12 is pivoted on a pin 13 in a slide 14 and supported on shoulder 15 of bracket 16 formed on slide 14. The slides 14 are guided for vertical movement in the main frame members of the bed, as indicated at 17 and 18 of Figure 3. This movement is effected by bell cranks 19 pivoted at 20 to the main frame members of the bed. See Figures 1 and 2. The arm 21 of each bell crank 19 is connected to slide 14 by means of link 22, and the other arm 23 is pivoted to a thrust rod 24 extending longitudinally of the bed. Motion imparted to rod 24, by any suitable motor driven or manually operated means of well known construction, causes the bell cranks 19 to turn on their pivots 20, thus raising or lowering the slides 14 and with them the arms 12. It will be apparent that the arrangement for raising and lower-

ing the apron 3 is similar to that just described and more fully shown for the slides 14.

Each arm 12 has an extension 25 pivotally connected by a pin 26 to a slotted link 23. The link 23 is pivoted at 29 to the main frame member of the bed. Faces 30 of the links 23 serve as guides for the arms 12, the ends of which are bifurcated, and the pins 26 are free to move in the slots 28a during the travel of slides 14 with arms 12, up or down, to adjust the position of the pack-supporting means to suit any particular width of bar to be handled. During such adjustments, therefore, the position of arms 12 is changed only as to elevation with respect to the packing section 7 of the cooling bed; i. e., the arms 12 are moved vertically but without angular change of position. When the slides 14 and the arms 12, have been elevated sufficiently by actuating rod 24, to cause pins 26 to engage the upper ends of slots 28a in links 23, further elevation of slides 14 by continued movement of rod 24, causes the arms 12 to tilt on pins 13. In this manner the arms 12 are moved angularly to the position shown in Figure 5, to restore to starting position the pack-supporting abutments (to be described) or to clear the bed in the interest of accessibility. Figure 6 shows the position of bell crank 19, link 22 and slide 14 corresponding to the position of arms 12 in Figure 5.

Whereas rod 24 serves to move the arms 12 collectively to adjust the pack-supporting means for different widths of bars or to bring the pack-supporting abutments to starting position, individual adjustment for alignment of arms 12 is also provided for. To this end, the links 22 are made in the form of turn-buckles, so their length can be adjusted to change the position of arms 12 for exact alignment. In addition to the abutments 34, we may also provide lower retreating abutments 34a, as fully disclosed in Fisk Patent No. 1,921,353.

A pack engaging latch member 31 is pivoted at 32 to each of the arms 12. The latch members are so positioned relative to their pivot pins that the projecting left hand ends of the members over-balance the right hand ends, whereby the latter normally engage the stops 33. The latch members 31 serve to support the pack on the entry side, as the flat bars of the pack are delivered on edge. A retreating abutment 34 is guided in tracks 35 on each of the arms 12 and is free to retreat when actuated by the delivery of bars to the packing section 7. The abutments 34 serve to support the pack on the discharge side by virtue of friction between abutments 34 and their tracks 35, due to the weight of the abutments. This support for the pack, however, may be augmented by using counterweights 36 connected to abutments 34 by cables 37, operating over guide pulleys 38 and serving to further resist the retreating motion of abutments 34. The counterweights 36 are preferably mounted for reciprocation inside the slides 14, which are made hollow for that purpose.

The tracks 35 for the retreating abutments 34 are inclined with respect to the packing position of section 7 of the cooling bed, so that the abutments 34 are pushed uphill during the formation of the pack. The abutments 34 have faces 39, which engage the side of the first bar delivered to form a pack, at a substantial depth below its top edge, and thus form a dependable support for the bar standing on its bottom edge. The abutment 34 is shown in dot and dash lines in this position in Figure 1. As bars are added to form

a pack on section 7 of the bed the abutments 34, guided in tracks 35, are forced to travel uphill so as to gradually reduce the depth of their engagement with the first bar of the pack and thus leave it free to drop from the pack by gravity, when the pack is completed and the first bar reaches the sloping discharge section 8 of the bed. The abutments 34 then cease to retreat and annealed bars drop by gravity from the discharge side of the pack as hot bars are added to the entry side. In addition to the abutments 34, we may also provide lower retreating abutments 34a, as fully disclosed in Fisk Patent 1,921,353.

The arms 12 with latch members 31 and abutments 34 are made narrow as shown in Figure 4 and are spaced along the length of the cooling bed to barely clear the packing arms 11 in their motion delivering bars to pack position. This arrangement reduces to a minimum the bending moment exerted on the bars by the force of the packing arms in displacing the latch members 31 and forcing the abutments 34 to retreat. It appears not to be necessary, however, to provide arms with pack-supporting means for every packing arm.

The manner in which the apparatus described above is operated to pack thin flat bars of any particular width for progressive cooling in contact with each other will now be explained. The rod 24 is first operated to swing the arms 12 to position shown in Figure 5, to cause the abutments 34 to slide to starting position. The motion of rod 24 is then reversed to cause the arms 12 to come to rest on shoulders 15 on brackets 16 of slides 14, and the motion of rod 24 is continued until the latch members 31 and the abutments 34 reach the proper level for supporting a pack of bars of the particular width to be handled. Such a setting for relatively wide bars is shown in Figure 1, whereas the setting of the pack-supporting mechanism for relatively narrow bars is shown in Figure 3. In case of bars of minimum width, the arms 12 are lowered still further to bring the abutments 34 to the dotted line position shown in Figure 3, where they reach below the top surface of the packing section 7 of the bed when they are in position to start a pack. Grooves are provided in the aprons of packing sections 7 to accommodate the abutments 34 without interference, or the skids of the packing section 7 may be spaced to accomplish this purpose. The proceedings are then identical, irrespective of width of bars handled.

The first bar is received by the conveyor rollers 2 and is kicked off by the side guards 5 to slide down the sloping skid section 4 of the bed. When the bar reaches the bottom of the sloping skid section, the shaft 10 is operated to swing the packing arms 11 to the position indicated in dot and dash lines in Figure 1. During this movement, the upper edge of the bar while supported by the faces of the packing arms 11 engages and displaces the projecting ends of the latch members 31. When the bar in transit has passed beyond the ends of the latch members, the latter fall back to their initial position, determined by stops 33. The shaft 10 is then operated in the opposite direction to return the packing arms 11 to their starting position below the face of sloping skid section 4. This position of the packing arms 11 is shown in dotted lines in Figure 1. The first bar thus delivered to the packing section 7, due to the force exerted by the packing arms 11, causes the abutments 34 to retreat sufficiently to make room for the bar thus

placed on edge, between the faces 39 of the abutments 34 and the faces 40 of the latch members 31. The delivery of additional bars to form a pack on section 7 of the bed causes the abutments 34 to retreat further in the same manner. As already explained the depth of engagement between the pack and the abutments 34 is gradually reduced as the pack increases in size. Thus, we fully support the bars of the pack in its early stage of formation and, at the same time, permit free discharge of the annealed bars from the completed pack.

With the original pack completed, as shown in Figures 1 and 3, it will be evident that the addition of another bar will cause the first bar of the pack to pass beyond the packing section 7 of the bed, whereupon it is free to fall down the relatively steeply inclined discharge section 8 for further handling by final cooling section 9.

20 A clean separation of each bar individually from the remaining bars of the pack results from the fact that the weight of the bar is much greater than the frictional force exerted thereon by the abutments 34, in their elevated position at the discharge side of the pack.

Continued operation through the above described cycle causes the discharge of the leading bar from the discharge side of the pack each time an additional bar is delivered to the entry side 30 of the pack. When the desired quantity of bar stock has been rolled and delivered to the pack-annealing section 7 of the bed, the last bars rolled form a "residual" pack. It fully covers the pack annealing section, where it is retained until its bars have been fully annealed by slow cooling. The pack-annealing section of the bed is then tilted by rotation of shaft 7a to cause the bars forming the residual pack to slide downwardly onto the final cooling or carry-over bed 40 9 for further handling.

This method of clearing the residual pack has certain drawbacks in common with established practices on existing cooling beds equipped for pack-annealing of flat bars. It is a source of delay to subsequent handling and shearing operations, which must wait during the time needed to cool the residual pack. It is also objectionable because of the considerable labor involved in separating the bars of the residual pack after they have been delivered to the final cooling or carry-over bed. The "dumping" of the residual pack from the pack-annealing section of the bed cause the bars to shingle in the wrong direction, in that the more advanced bars in the pack become more or less pinched or covered by subsequent bars, and the job of extracting them from the pack thus involves considerable effort and much labor.

60 In a modified form of our invention, as illustrated by Figures 8 and 9, these difficulties pertaining to the residual pack are eliminated and the labor required is very much reduced. To this purpose the tracks 35 for the abutments 34 are made horizontal, with the arms 12, latch members 31 and abutments 34 in packing position. Just the same, the abutments 34 are caused to recede from contact with the pack by tilting the packing section 7 on shaft 10 to an appropriate angle, as illustrated in Figures 8 and 9 for wide and narrow bars respectively. The abutments 34 can thus be made to support a pack of bars of predetermined size up to the capacity of the packing section of the bed.

75 To effect delivery of the flat bars in inclined

position on the annealing section of the bed, as shown in Figures 8 and 9, the packing arms 11 are so shaped that their working faces 41 automatically deliver the bars to the pack at desired inclinations. The stopping point of the packing arms 11, for such delivery, is adjusted for different widths of bars, to deliver them past the latch members 31 and allow these latch members to drop to holding position.

During the packing process the operations are the same as described above for flat bars vertically disposed in pack formation. When the desired quantity of bar stock has been rolled and delivered to the pack-annealing section, however, the then remaining residual pack can readily be disposed of, without delay, to subsequent handling and shearing operations.

By placing a man at either end of the packing section, the bars of the residual pack, now sloping in the desired direction, can easily be separated manually from the pack and caused to slide down the discharge section 8 onto the final cooling section 9. If the rate of discharge of bars from the packing section be maintained at the rate prevailing during the packing process, then the time for cooling the bars of the residual pack will also remain the same, and the speed of subsequent handling and shearing operations will remain unchanged.

Several of the advantages of our invention have been mentioned above in the course of the detailed description. By placing the bars vertically on edge, in pack formation, and by supporting the bars of the pack against over-turning in either direction, dependable means are provided to maintain the stability of the pack during all stages of the packing process. In this respect, the invention is a marked improvement over prior pack-annealing cooling beds which depend upon friction alone due to the weight of the bars in inclined position, or on lateral support in one direction only, to maintain the pack. Furthermore, the invention provides an improved cooling bed having simple and relatively inexpensive provisions for the pack annealing of bars of various widths up to any maximum the cooling bed as a whole is suited to handle. In addition, by virtue of the particular motion of the retreating abutments, which firmly support the bars against over-turning during all stages of the packing process but still leave them free to drop at the discharge side of the packing bed, the leading bar of the pack separates itself quickly and cleanly from the remainder of the pack as a succeeding bar is delivered to the entry side thereof. In a modified form of the invention, as illustrated by Figures 8 and 9, we have also overcome some inherent difficulties in disposing of the residual pack, as already explained.

Although we have illustrated and described but two preferred embodiments of the invention, it will be recognized that changes in the construction and arrangement may be made without departing from the spirit of the invention or the scope of the appended claims.

We claim:

1. In a cooling bed having a section for pack-annealing of thin flat bars which do not stand on edge without lateral support, means for placing bars vertically on edge to form a pack and means to laterally support bars thus placed against over-turning in both directions, said last-mentioned means including traveling abutments initially engaging the side of the leading bar of the pack, and moving at an angle to the plane of

said section so as finally to engage the upper edge of the leading bar.

5. In a cooling bed having a section for pack-annealing thin flat bars which do not stand on edge without lateral support, means for placing bars on edge to form a pack, pivoted supports engaging the bar last placed, traveling abutments initially engaging the side of the leading bar of the pack and means guiding said abutments along a path at an angle to the plane of said section whereby said abutments finally engage the upper edge of the leading bar.

10 15 3. In a cooling bed having a section for pack-annealing thin flat bars which do not stand on edge without lateral support, means for placing bars on edge to form a pack, displaceable latch members engaging the last bar placed, and traveling abutments engaging the leading bar of the pack, said members and traveling abutments being adjustable for bars of different widths, and common means for adjusting said members and abutments.

15 20 25 4. In a cooling bed having a section adapted for pack-annealing thin flat bars incapable of standing on edge to form a pack without lateral support, means for delivering bars on edge successively to said section, supports overhanging said section, rear abutments mounted on said supports for displacement by successive bars, said abutments being adapted after passage of a bar to engage the latter and thereby hold the pack of previously delivered bars from overturning rearwardly, and forward abutments on said supports adapted to be engaged by the first bar in the pack, said forward abutments being movable along said supports as the pack is built up.

20 25 30 45 5. In a cooling bed having a section adapted for pack-annealing thin flat bars incapable of standing on edge to form a pack without lateral support, means for delivering bars on edge successively to said section, supports overhanging said section, rear abutments mounted on said supports for displacement by successive bars, said abutments being adapted after passage of a bar to engage the latter and thereby hold the pack of previously delivered bars from overturning rearwardly, and forward abutments on said supports adapted to be engaged by the first bar in the pack, said forward abutments being movable along said supports as the pack is built up, said rear abutments being latch members pivoted to said supports.

35 40 45 50 55 60 65 70 75 6. In a cooling bed having a section adapted for pack-annealing thin flat bars incapable of standing on edge to form a pack without lateral support, means for delivering bars on edge successively to said section, supports overhanging said section, rear abutments mounted on said supports for displacement by successive bars, said abutments being adapted after passage of a bar to engage the latter and thereby hold the pack of previously delivered bars from overturning rearwardly, forward abutments on said supports adapted to be engaged by the first bar in the pack, said forward abutments being movable along said supports as the pack is built up and means for adjusting said supports in order that the abutments may cooperate with bars of different widths.

70 75 80 85 90 95 7. In a cooling bed having a section adapted for pack-annealing thin flat bars incapable of standing on edge to form a pack without lateral support, means for delivering bars on edge successively to said section, supports overhanging said section, rear abutments mounted on said

supports for displacement by successive bars, said abutments being adapted after passage of a bar to engage the latter and thereby hold the pack of previously delivered bars from overturning rearwardly, forward abutments on said supports adapted to be engaged by the first bar in the pack, said forward abutments being movable along said supports as the pack is built up, and means for tilting said supports in order to restore said forward abutments to pack-starting position.

8. In a cooling bed having a section adapted for pack-annealing thin flat bars incapable of standing on edge to form a pack without lateral support, means for delivering bars on edge successively to said section, supports overhanging 15

said section, rear abutments mounted on said supports for displacement by successive bars, said abutments being adapted after passage of a bar to engage the latter and thereby hold the pack of previously delivered bars from overturning rearwardly, and forward abutments on said supports adapted to be engaged by the first bar in the pack, said forward abutments being movable along said supports as the pack is built up, said supports being disposed at an angle to the pack-annealing section whereby said forward abutments gradually move away from said section as a pack is built up thereon.

GUSTAF L. FISK.
